UNITED STATES PATENT OFFICE

2,196,045

NOZZLE DIAPHRAGM

Glenn B. Warren, Niskayuna, and Hezekiah Haigh, Scotia, N. Y., assignors to General Electric Company, a corporation of New York

Application June 3, 1938, Serial No. 211,592

3 Claims. (Cl. 253—78)

The present invention relates to nozzle diaphragms such as are used in an elastic fluid turbine for conducting elastic fluid to bucket wheels. More particularly, the invention relates to the type of nozzle diaphragms which includes a nozzle structure having inner and outer bands and a plurality of spaced nozzle blades secured to the bands and forming nozzle passages for directing the flow of elastic fluid to a bucket wheel.

10 An arrangement of this kind is disclosed in the patent to H. A. Lacey, No. 1,932,278, issued October 24, 1933, and assigned to the same assignee as the present invention. The outlet edges of the nozzle blade are thin and when exposed to the high pressures and temperatures in modern elastic fluid turbines they are subjected to excessive strains and stresses which may lead to damage of the thin edges especially in case the thin edges are integrally mounted or formed with bands or side walls.

15 The object of our invention is to provide an improved nozzle diaphragm whereby strains and stresses to which the outlet edges of the nozzle blades are subjected are considerably reduced.

20 For a consideration of what we believe to be novel and our invention, attention is directed to the following description and the claims appended thereto in connection with the accompanying drawing.

25 In the drawing, Fig. 1 illustrates a sectional view through a turbine nozzle diaphragm and bucket wheel arrangement embodying my invention; Fig. 2 is a view along line 2—2 of Fig. 1; and Fig. 3 is a view along line 3—3 of Fig. 2.

30 The arrangement comprises a nozzle structure with a plurality of circumferentially spaced nozzle blades 10 having thin outlet edges 11 and inner ends secured to or integrally formed with an inner band 12 and outer ends secured to or

35 integrally formed with an outer band 13. The securing of the ends of the blades to the inner and outer bands may be accomplished by welding in the manner set forth in the afore-mentioned patent to Lacey. The inner band 12 is seated in the present arrangement in a recess 14 of a disk 15 and united with the latter by a weld 16.

40 The outer band 13 is seated in a recess 17 of a solid outer ring 18 and united therewith by a weld 19. The nozzle structure forms passages

45 20 between adjacent nozzle blades for conducting elastic fluid to a bucket wheel which has a plurality of buckets 21 with inner ends suitably fastened to a disk or wheel 22 and outer ends connected by a shroud band 23.

50 In order to prevent excessive strains and

stresses from being set up in the thin outlet portions 11 of the nozzle blades 10, the end portions of the inner and outer bands 12 and 13 near said thin outlet portions 11 are made resilient. In the present example the inner and outer bands have end portions 24 and 25 which are reduced in thickness. These thin portions 24 and 25 are not directly secured to the disk and ring by the welds 16 and 19 respectively and thus they are free to expand in radial direction. An 10 arrangement of this kind is described in the application of John H. Doran filed on the same date as the present application.

55 The nozzle structure with the inner and outer bands after assembly with the disk and the outer ring form large grooves to be filled by welds 16 and 19. In order to facilitate the provision of the weld 16 we provide in accordance with our invention a welding shield which may be in the form of a ring 26 uniformly spaced 20 from the reduced end portion 24 of the inner band 12 and forming therewith a gap or slot 27. Similarly, a welding shield or ring 28 is provided to facilitate the provision of the weld 19 and to form a gap or slot 29 with the reduced portion 25 of the outer band 13. These welding shields 26 and 28 have another important function in that they form sealing surfaces in cooperative relation with sealing strips 30 and 31 secured to the disk 22 and the shroud band 23 respectively 30 of the bucket wheel.

After welding, the welding shields or rings 26 and 28 form a unitary structure with the inner and outer bands and it is clear that the same result may be accomplished by making these 35 welding shields an integral part of the inner and outer bands and thereafter machining the slots 27 and 29 into end portions of these bands. In other words, solid bands such as disclosed, for instance, in the above patent to Lacey may 40 be used and in order to provide flexibility of their end portions, these portions may be machined to form slots near the thin edge portions of the nozzle blades. Thus, applicants' bands and welding shields together constitute band 45 structures which have an edge portion circumferentially slotted to render resilient a part of such portion secured to the thin outlet portions of the blades.

Having described the method of operation of 50 our invention, together with the apparatus which we now consider to represent the best embodiment thereof, we desire to have it understood that the apparatus shown is only illustrative and that the invention may be carried out by other means. 55

What we claim as new and desire to secure by Letters Patent of the United States is:

- 5 1. A nozzle diaphragm including a band structure, a plurality of nozzle blades with thin outlet edges and ends secured to the band structure, the portion of the band structure secured to and in proximity to the thin outlet portions being circumferentially slotted to render such band resilient and thereby to eliminate excessive strains and stresses in the thin outlet portions.
- 10 2. A nozzle diaphragm comprising a plurality of nozzle blades having thin outlet edges, a band united with the ends of the blade, a solid member forming a seat for the band, the band having a portion reduced in thickness secured to the thin outlet portions, a welding shield uniformly spaced

with the reduced band portion, and a weld uniting the band with the solid member and the welding shield.

- 15 3. A nozzle diaphragm comprising a plurality of spaced nozzle blades having thin outlet edges, inner and outer bands secured to the ends of the blades, said bands having portions reduced in thickness near the outlet edges of the blades, inner and outer welding shields forming narrow gaps with the reduced inner and outer band portions, a disk, a weld uniting the inner band and welding shield with the disk, a ring, and a weld uniting the outer band and welding shield with the ring.
